(57) **CLAIM**

The ornamental design for a log splitter, as shown and described.

DESCRIPTION

FIG. 1 is a front view of the log splitter, the back view being an identical view thereto;

FIG. 2 is a right view thereof, the left view being an identical view thereto;

FIG. 3 is a top view thereof;

FIG. 4 is a bottom view thereof;

FIG. 5 is a first perspective view thereof; and,

FIG. 6 is a second perspective view thereof.

The superimposed areas incased in broken lines, shown in FIGS. 1, 2, 3, 5 and 6, illustrate portions of the log splitter and form no part of the claimed design.
